UNITED STATES PATENT OFFICE.

LOUIS W. WANEMAKER, OF CHICAGO, ILLINOIS, ASSIGNOR TO THE WINDOW VENTILATOR COMPANY OF AMERICA, A CORPORATION OF ILLINOIS.

WINDOW-VENTILATOR.

1,261,196.

Specification of Letters Patent.

Patented Apr. 2, 1918.

Application filed March 8, 1916. Serial No. 82,794.

To all whom it may concern:

Be it known that I, LOUIS W. WANEMAKER, a citizen of the United States, residing at Chicago, in the county of Cook and State of Illinois, have invented certain new and useful Improvements in Window-Ventilators, of which the following is a specification.

My invention relates to improvements in window ventilators and particularly to a ventilator for coöperation with the ordinary vertically-sliding, handle-equipped, lower sash of customary window construction.

One object of my invention is to provide a ventilator which will accommodate the customary lifting handle of the sliding sash and will normally coöperate therewith to limit the sliding movement of the sash to that which will open or close the intake of the ventilator, but which is bodily tilt-able without disconnection from the window casing to permit raising of the window sash to its full height.

Another object of my invention is to provide a ventilator having, for its ejection opening, a closable register which, accordingly as it is partly or wholly open, will deflect the incoming air upwardly on lines 30 respectively back toward the window pane, or very nearly a parallel to the plane of the window, thus avoiding the admission of a direct draft on the persons in the room.

A further object of my invention is to provide a simple and efficient register or shutter mechanism for regulating the amount of air permitted to flow into the room, and so to construct and arrange such mechanism that its operation will be affected little, if any, by rusting of the parts.

Another object of my invention is to make adequate provision for adjustment of the ventilator-frame to the window-casing to compensate for variations in window casing dimensions and to facilitate properly-fitting installation.

Still another object of my invention is to provide a ventilator structure that, when in place, is very firmly fastened and may not be tampered with from the outside of the room, but which may be bodily removed from the window casing, by one in the room, without the use of tools and without detaching any small parts; and a still further

object is to provide a structure for permanent association with the window casing to detachably support the ventilator frame, which is small, inconspicuous, and attachable without material damage to the wood-work.

Other and further objects of my invention will become apparent to those skilled in the art from the following description taken in conjunction with the accompanying drawings, wherein—

Figure 1 is a perspective view of a window showing my improved ventilator attached to the casing thereof.

Fig. 2 is a front elevation of a ventilator as attached to a window with parts broken away to show the shutters.

Fig. 3 is a transverse sectional view on the line 3—3 of Fig. 2.

Fig. 4 is a sectional view on the line 4—4 of Fig. 2 showing the ventilator tilted inwardly to permit the raising of a window-sash beyond the point where the sash-lift or handle would normally engage the ventilator-casing.

Fig. 5 is a fragmentary sectional view on the line 5—5 of Fig. 2.

Fig. 6 is a fragmentary sectional view on the line 6—6 of Fig. 2, and;

Fig. 7 is a fragmentary sectional view on the line 7—7 of Fig. 3.

In the drawings, 10 indicates an upper window sash, and 11 a lower sash, slidable in a window-casing 13.

The ventilator frame, somewhat shorter than the width of the suitable window casing, comprises in the particular construction shown a narrow bottom board 14, a wider head-structure 15, and connecting end walls 16, all alining vertically at their outer edges, so that when the frame rests upon the window sill 17, just inside of the lower window sash 12, the window sash may be raised and lowered to open and close the unobstructed rear or intake side of the ventilator. The customary lifting handle 12' of the sash, 90

however, acts as a stop to strike against the head wall of the ventilator frame and limit, normally, the range of movement of the lower window sash. The front wall 18 of the ventilator may be a plate of glass, or other material, slopingly mounted to deflect upwardly the incoming air impinging thereon and to drain outwardly any moisture that

strikes or collects thereon, such drainage being furthered by sloping the bottom board 14 toward its outer edge. A packing 38 may be used to make weather-proof connection 5 between the bottom board and the window sill.

The head 15, that affords the air-delivery outlet, is a rectangle formed by the rear and front strips 19 and 20, secured to the end 10 boards 16—16 and divided into panels as by a cross bar 21 that gives central bearing to the register mechanism to be described. Dust screens 22 of fine wire mesh cover the panel openings.

15 To support the ventilator frame in a window casing, I have provided a pair of angle irons 23—23, each of a height approximately equal to the height of the ventilator frame, for permanent attachment as by means of 20 the screws 24 to the opposite sides of window casing, the inturned legs of the irons lying flush with the window sash. Secured to the angle iron at the top and bottom are extension plates 25 and 26, the upper of 25 which is provided with a hole 27 and the lower of which is provided with a vertical slot 28, these openings receive members carried by the ventilator frame to support and position the latter. Secured to the ventilator end-members 16, along the vertical edges 30 which lie in proximity to the window casing, are vertical channel-bars 29 of a width sufficient each to receive a wooden extension board 30. The board is clamped in the channel by screws 31 which pass through openings in one side wall of the channel and are screw threaded into the opposite wall. The boards are provided with edge opening slots 31' through which the screws pass so 40 that when the extension boards 30 are positioned to make neat contact with the angle bars or supporting brackets 23 the screws may be tightened, thus securing the extension boards to the ventilator in proper adjusted position. This manner of adjusting the overall width of the ventilator frame is for the purpose of allowing for slight differences in window width due to shrinkage or other causes, and it insures that, as erected, 45 each ventilator frame will adequately fill the sash opening.

I hang the ventilator frame in the brackets 55 so that the ventilator structure may be readily removed in its entirety from the brackets by a person within the room (though not by one outside of the window) and I make the ventilator tiltable in the brackets, so that head 15 may act as a movable stop with respect to the window sash handles 12'. Thus, near the bottom of the extension boards 30 I provide slide bolts 32 for engagement with the slots 28 of the angle bar plates 26 to act, on occasion, as sliding pivots. Bolts 32 slide in holders 33 each of 60 which is provided with a flat leaf spring 34

that engages a cross pin 35 on the bolt to spring-latch the bolt in normal, projected position, engaging slot 28 of the bracket. To disengage the pivot bolt 32 from the sash-bracket, spring 34 is pressed back and 70 the bolt is retracted. At the top of each extension board 30 I have provided a spring pressed plunger bolt 36 carried in a holder 37 for normal engagement with the opening 27 in the supporting bracket plate 25, such 75 bolt being provided with a finger-piece for easy retraction.

By means of the fastening arrangement above described, the four bolts may be readily slid out of the bracket-openings 27, 28, 80 and the ventilator quickly removed from the window. With the ventilator in place it is obvious that while the window can be shut it cannot be raised above such a point as will bring the window handle 12' into contact 85 with the head 45. When in place it is obvious that the ventilator serves as an additional window lock. If it becomes necessary to raise the window still farther the operator simply slides the upper set of bolts 36 out 90 of engagement with the plates 25 and then tips the ventilator inwardly as shown in Fig. 4 so that the handle may clear the head 15, the bolts 32 sliding upwardly in slots 28, and the window can then be raised as far as 95 desired. A particular advantage of this bolted-on construction is that there are no loose parts that may become lost or misplaced when a servant removes the ventilator, as for window washing. 100

The register-shutter mechanism herein shown comprises a double set of shutter bars, one set placed under each of the openings in the head 15, both sets being operable simultaneously. Bars of suitable number, 105 in the particular instance illustrated, three, are employed in each shutter, and comprise flat metal strips 50, the ends of which are downturned at 51 and are perforated to receive the pivotal rods 52. The width of the 110 strips 50 is such that when swung about their pivots into a horizontal position, they will completely or substantially close the apertures in the top frame 15. The pivotal rods 52 which extend through the downturned ends 51 of the strips extend across the entire length of the openings in the top frame and near their centers are journaled in the opposite down-turned legs 53 of a broad channel-bar 54 secured to the cross-member 21 of the head. At their ends these rods pass through holes in the inner of the two downturned legs 55 of the narrow channel bars 56, the outer legs of which serve as end abutments to prevent axial displacement of the rods after they are positioned. 120

A shutter operating stem 57 is slidable through an aperture at the center of the frame bar 19 and carries a knob 58 on its outer end for convenient manipulation. 130

Near its inner end it is perforated to receive the U-shaped yoke or link 59 which, at its ends, is pivoted to the screws 60 which take into the shutter-connecting bars 61. These 5 bars lie along the edges of each of the legs 53 of the channel 54 and are pivotally connected as at 62—62 to each of the inturned ends 51 of the shutter strips 50. By means of this link connection it is obvious that 10 when the stem 57 is moved outwardly it carries with it the shutter operating bars 61 thus turning the shutters about their pivot rods and closing the openings in the top frame. A particular feature of advantage 15 incident to the mounting of the shutters upon the rods 52 which in turn are journaled in the narrow pressed metal supporting legs 53 and 55 is that a plurality of journals are provided, each of which is comparatively 20 narrow. Obviously such a structure is exposed to the elements and rain will in time rust the metal parts even though they be enameled or japanned most carefully. In this construction the journals are so narrow 25 that rust can unite only small surfaces, and the rust-union cannot be strong enough to afford very great resistance to shutter movement, especially as the shutters are free to turn either upon the rods or with the rods, 30 if the latter turn within their supporting journals.

In order that the shutter-setting mechanism may not work so easily, as to be liable to be closed by sudden gusts of wind, and 35 to aid in guiding bar 57, I have provided a frictional spring 63 which bears against the under side of the shutter operating stem 57, and presses the flat top surface of the stem against the rods 52.

40 While I have illustrated and described a single embodiment of my invention it is obvious that various changes might be made therein without departing from the spirit of the invention or the scope of the appended 45 claims.

Having described my invention, what I claim is:

1. The combination of a ventilator adapted for attachment to a window casing having 50 a pair of vertically spaced apart apertures at both sides thereof, and slide bolts carried by the ventilator, for engagement with the apertures, the lower of which is vertically elongated to permit vertical movement of 55 the bolts within the lower apertures when

the upper bolts are withdrawn from their apertures.

2. In a window ventilator, the combination with a window casing and sliding sash having an inwardly extending projection thereon, of a ventilator casing open at its front to receive and permit movement of the projection, and act as a limitation stop for the projection, and manually releasable means to lock the ventilator casing in the window casing and prevent vertical movement thereof. 60 65

3. The combination with a ventilator adapted for connection with a window casing, of vertically disposed angle bars secured to the casing with one leg of each bar turned inwardly and lying in a plane parallel with the window and positioned for contact with the inner face of the window sash, plates secured to the top and bottom portions of 70 each bar, each said plate having an opening therein, and slide bolts carried by the ventilator for engagement with the openings. 75

4. In a window ventilator, the combination with a window casing and sliding sash having a lift handle, of a ventilator casing open at its front to receive and permit movement of the window sash handle, and act as a limitation stop therefor, means tiltably supporting the frame in the sash to permit its 80 movement to allow the sash-handle to pass by for full window opening, and releasable means for locking the ventilator against such movement. 85

5. The combination of a ventilator adapted for attachment to a window casing at the inner side of the plane in which the window slides, and releasable fastening means for attaching the ventilator to the casing at vertically spaced apart points, the lower fastening means permitting partial rotation of the ventilator with respect to the casing when the upper fastening means are released, said upper fastening means being accessible from the inner side of the window only and adapted when in position to lock the ventilator 95 from movement. 100

In testimony whereof I hereunto set my hand in the presence of two subscribing witnesses.

LOUIS W. WANEMAKER.
